UNITED STATES PATENT OFFICE.

WILLY FELLER, OF ESSEN-ON-THE-RUHR, GERMANY, ASSIGNOR TO FRIED. KRUPP AKTIENGESELLSCHAFT, OF ESSEN-ON-THE-RUHR, GERMANY.

AMMUNITION-CHEST.

1,212,201.

Specification of Letters Patent. Patented Jan. 16, 1917.

Application filed February 18, 1915. Serial No. 9,118.

To all whom it may concern:

Be it known that I, WILLY FELLER, residing at Essen-on-the Ruhr, Germany, a citizen of the German Empire, have invented a 5 certain new and useful Improvement in Ammunition-Chests, of which the following is a specification.

The present invention relates to ammunition chests and the object of the invention is 10 to provide such chests with a device, which permits the securing of ammunition of different length, as for instance, a complete round of cartridge and projectile or a projectile alone, in each pigeon hole of the chest 15 intended to contain an ammunition unit.

In the accompanying drawing is shown, as an embodiment of the invention, a chest constructed to contain three ammunition units, as for instance shrapnel cartridge or 20 cartridges with torpedo shells.

Figure 1 shows a vertical section of the chest and Fig. 2 a section along line 2—2 of Fig. 1.

The chest A is provided with a lid A¹, 25 which is connected with the chest by means of hinges a², Fig. 2. The chest A has transoms B and C, in which cylindrical bearings b¹ and c¹, respectively, are pressed out. In these bearings the ammunition F G may 30 rest with slight play. On the bottom a³ of the chest is attached a flat liner E of rubber or the like, upon which the projectiles may rest with their flattened heads.

On the inside of the lid A¹ are rigidly 35 secured two L-shaped bearing pieces H. With the free ends of the shanks of these bearing pieces, are linked three stirrups K, through the intermediary of studs k¹. Each stirrup K may be secured on the bearing 40 piece H in two positions, displaced 180° relative to each other, by means of spring latches. These latter comprise projections m¹ provided on flat springs M and notches h¹ and k² respectively for the projections. 45 As shown in Fig. 1, the flat springs M are either secured on a shank of the bearing pieces H, or on the shanks of the stirrup K. The notches h¹, k², for the projections m¹ of the flat springs M, are therefore correspondingly provided either on the stirrups K or on the bearing pieces H. On both 50 sides of the rung of each stirrup K, is secured a flat liner k³ of leather or the like, which has the function to rest against the 55 base of the cartridge case.

If the stirrups K have the position illustrated in the drawing, wherein they are secured by means of the spring latches m¹, h¹ or k², respectively, two long cartridges with torpedo shells F and one short shrapnel cartridge G may be inserted in the chest. 60 The cartridges are then suspended between the stirrups K or the flat liners k³ and the bottom liner E, when the lid A¹ is closed.

Should for instance the pigeon hole situated to the left in Fig. 1 of the drawing 65 serve to hold a shrapnel cartridge, the stirrup K in question is then to be turned 180° after the lid A¹ has been opened. The projections m¹ are then disengaged from the lower notches h² and k¹, while the flat 70 springs are being tensioned. After completion of the above mentioned turning of the stirrup K, the projections m¹ of the springs M snap into the upper notches h¹ 75 and k², so that the stirrup is secured against turning in its new position. The described device consequently permits the inserting of either a long or a short ammunition unit, 80 that is a projectile or a cartridge, in each pigeon hole of the chest.

I claim:

1. An ammunition chest having a fixed abutment and an adjustable abutment for holding securely between them in axial direction ammunition of different length.

2. An ammunition chest having a fixed abutment and a reversible abutment for holding securely between them in axial direction ammunition units of different length, 90 there being also cylindrical bearings in the chest supporting the ammunition transversely with some play.

3. In an ammunition chest with fixed bottom and sides, a stirrup hinged in the 95 chest, and means for securing said stirrup in either of two axially opposite positions, whereby ammunition units of different length may be suspended between said bottom and said stirrup, there being also cylindrical bearings in the chest supporting the ammunition transversely with some play.

4. In an ammunition chest with fixed bottom and sides and a lid; a bearing piece attached under the lid, depending shanks on 105 said bearing piece, a stirrup journaled at the free ends of said shanks, and means for securing said stirrup in either of two diametrically opposite positions, whereby ammunition units of different length may be 110

suspended between said bottom and said stirrup.

5. In an ammunition chest with fixed bottom and sides and a lid; a bearing piece attached under the lid, depending shanks on said bearing piece, a stirrup journaled at the free ends of said shanks and constructed to have two positions 180° apart from each other, a snap latch between said stirrup and 10 said bearing piece for securing said stirrup in either one of said two positions.

6. In an ammunition chest with fixed bottom and sides and a lid; a bearing piece attached under the lid, depending shanks on 15 said bearing piece, a stirrup journaled at the free ends of said shanks and constructed to have two positions 180° apart from each other, a snap latch between said stirrup and said bearing piece for securing said stirrup 20 in either one of said two positions; said

snap latch comprising a flat spring with a projection for engaging in corresponding notches.

7. In an ammunition chest with fixed bottom and sides and a lid; bearing pieces attached under the lid, depending shanks on 25 said bearing pieces, stirrups journaled at the free ends of said shanks and constructed to have two positions 180° apart from each other, a snap latch between said stirrups and 30 said bearing pieces for securing said stirrups in either one of said two positions.

The foregoing specification signed at Barmen, Germany, this 7th day of January, 1915.

WILLY FELLER. [L. s.]
